EDGAR G. MORIN
INVENTOR.

BY *Munn & Co.*

ATTORNEYS.

UNITED STATES PATENT OFFICE.

EDGAR G. MORIN, OF SAN FRANCISCO, CALIFORNIA.

DOOR HANGER AND ADJUSTER.

1,370,037.

Specification of Letters Patent. Patented Mar. 1, 1921.

Application filed September 16, 1920. Serial No. 410,599.

To all whom it may concern:

Be it known that I, EDGAR G. MORIN, a citizen of the United States, and resident of San Francisco, county of San Francisco, 5 State of California, have invented a new and useful Door Hanger and Adjuster, of which the following is a specification.

This invention relates to improvements in hangers for sliding doors.

10 The primary object of the invention is to provide a hanger of the character described which is simple as to construction, inexpensive, reliable in use, practically noiseless, capable of being readily and easily adjusted so that the door may be hung properly 15 in the frame and which may be easily assembled and fitted without necessitating any change in the door frame or wall construction or the provision of special wall and 20 door frame construction.

Another object of the invention is to provide in a hanger of the character described 25 novel, effective, easily operable and reliable means for effecting a vertical adjustment in the door after the latter is hung whereby the door will operate properly in the frame.

The invention possesses other advantages 30 and features, some of which, with the foregoing, will be set forth at length in the following description wherein I shall outline in full that form of the invention which I have selected for illustration in the drawings accompanying and forming a part of the present specification. In said drawings 35 I have shown one form of the construction of my invention but it is to be understood that I do not limit myself to such form, since the invention as expressed in the claims may be embodied in a plurality of 40 forms.

Referring to the drawings, Figure 1 is a perspective view broken away and partly in section of the hanger of this invention; Fig. 2 is a detail perspective view of the 45 adjusting plate; Fig. 3 is a perspective view of the hanger body or casing; Fig. 4 is a fragmentary perspective view of the cover plate for the body or casing; Fig. 5 is a side elevation of the hanger showing part of 50 the door and wall in section and the hanger as it would appear when set up and Fig. 6 is a detail perspective view of the adjusting nut.

The present embodiment of the invention 55 generally comprises a casing or body (1) which is countersunk in the top of a door

(2), means for vertically adjusting the door mounted in the casing and a strap hanger (3) attached to the adjusting means and casing and to the wall track member (4) 60 which latter is disposed between the headers of the wall above the door frame, not shown. The casing or body is formed of sheet metal bent into U shape, with the sides (5) and (6) provided at their upper edge 65 with lateral apertured ears (7). A cover plate (8) is mounted upon the upper side of and closes the casing, said plate being provided with apertures (9) which register with the aperture of the ears (7). One end 70 of the plate (8) is reduced and turned downwardly to provide a flange (10), which partially closes one end of the casing.

The casing is countersunk in the upper edge of the door (2) and held in place by 75 screws (11) which are inserted through the apertures of the plate (8) and ears (7) into the door. Preferably two hangers are employed for a door and are arranged thereon with certain ends projecting through 80 the vertical edges of the door. The adjusting plate (12) engages the inner face of the plate (8) and is movable longitudinally in the casing (1) by screw (13) rotatable in a bearing (14) therefor formed 85 in the sides (5) and (6) of the casing. This screw projects out of one end of the casing so as to abut the flange (10). This flange extends only part way over the screw head (14) and is notched as at (15) opposite 90 said head to permit of access thereto with a screw driver. The screw is at the end of the casing which is exposed at the edge of the door as shown in Fig. 5 whereby it may be conveniently reached and actuated. 95

The plate (12) has a slot (16) therein in which the screw turns freely. The slot (16) is provided on opposite sides and intermediate of its ends with enlargements (17) in which an angular faced nut (18) 100 is snugly and non-rotatably fitted, said nut bearing on opposite sides in slots 16^a in the sides of the casing 1. The screw surrounding portions 17^a of the casing 1 are tubular as shown. The screw is turned through the 105 nut and may be rotated to move the plate (12) longitudinally in either direction in said casing.

A plate (19) is arranged in the casing (1) so as to move the plate (12) vertically with 110 the door carried thereby. This plate (19) is provided with a lateral projection (20) which

is movable in the slot (21) formed in the side of the casing (1). At the end of the plate (19) are angular projections (22) extending at right angles to the plate and arranged to move in inclined slots (23) formed in the plate (12). By reason of the projections (20) and slots (21) preventing longitudinal movement of the plate (19), when the plate (12) is adjusted longitudinally the angular projections (22) are caused to move in the inclined slots so that the plate (12) moves vertically.

On the upper edge of the plate (19) is a dovetail projection (24) fitted in a socket (25) therefore in the lower end of the hanger (3) so as to removably and rigidly connect the hanger with the vertically adjustable plate (19). The cover plate is slotted as at (26) to permit the hanger to extend therethrough into the casing. The slot is wider than the hanger is thick so as to permit the hanger to be inserted in the casing and be moved laterally into position to interlock with the dovetail projection.

The strap hanger extends upwardly through the jamb, not shown, and between the headers of the wall, also not shown. On the upper wall of the hanger a roller (27) is carried so as to ride upon the track member (4). The hanger has an offset portion (28) which is adapted to abut the lower part of the track member (4) to prevent the hanger from moving upwardly.

With the hanger set up as described herein the door will be hung for sliding movement in such a way that the sliding operation will be certain, smooth and noiseless, it being possible to hang the door quickly and easily without changing the door and wall construction appreciably. To adjust the door in the frame whereby it will hang properly the screw (13) is turned one way for raising the door and another for lower-

ing it. When the screw is turned to the right the plate (12) is drawn horizontally toward the screw, and the projections (22) in bearing upon upper sides of the inclined slots (23) cause the plate (12) to move upwardly of the plate (19) and the door is thus raised to a desired point so as to hang properly. By turning the screw in the opposite direction the door is lowered.

I claim:

1. A door hanger embodying in its construction a slidably suspended hanger strap, a door carried casing, a closure plate for the casing having an opening therein through which the strap extends into said casing, a plate in the casing with which the strap is connected, guide pins on the plate, said casing having upright slots therein receiving the guide pins and means which when moved longitudinally in the casing relative to said plate effects a vertical adjustment of the casing relative to said plate.

2. A door hanger embodying in its construction a slidably suspended hanger strap, a door carried casing, a closure plate for the casing having an opening therein through which the strap extends into said casing, a downwardly presented end on said plate adapted to overlie the end of the door and having an opening therein, a plate in the casing with which the strap is connected, guide pins on the plate, said casing having upright slots therein receiving the guide pins and means which when moved longitudinally in the casing relative to said plate effects a vertical adjustment of the casing relative to said plate, comprising a plate having a screw connected therewith, the head of said screw being presented exteriorly of the end of the door through the opening in the downwardly presented end of said closure plate.

EDGAR G. MORIN.
